UNITED STATES PATENT OFFICE.

JESSE LOCKHART, OF NIANTIC, ILLINOIS.

RAIL-BED FOR ELEVATED RAILWAYS.

SPECIFICATION forming part of Letters Patent No. 250,372, dated December 6, 1881.

Application filed August 27, 1881. (No model.)

To all whom it may concern:

Be it known that I, JESSE LOCKHART, a citizen of the United States, residing at Niantic, in the county of Macou and State of Illinois, 5 have invented a new and useful Rail-Bed for Elevated Railways, of which the following is a specification, and which has never been patented to me nor to others with my knowledge and consent in any foreign country.

10 My invention relates to rail-beds for elevated railways, in which "ties" are dispensed with and the rails bolted to the bed in a manner that permits free lateral expansion and contraction.

15 The object of my invention is to produce a bed and mode of attachment that will, in combination with the rail used, (which has been previously patented in the United States by me,) tend to lessen the noise peculiar to elevated railways.

20 In the drawings, Figure 1 is a portion of the device in side elevation. Fig. 2 is a plan, and Fig. 3 an end view, of the same. Fig. 4 shows a transverse section of the device used to secure the rail to the bed.

25 O represent the bed resting on a stringer, A, and provided with rims B and C, the first mentioned, B, acting as an outer guard for the car-wheels in case of a derailment. The stringer 30 A, the bed O, and the fenders B C are made

from pieces of metal, bent as shown, united beneath the bed O and bolted together to form the stringer A. The fender B is preferably higher than the fender C.

D is the rail held in lateral position by blocks 35 i i, and bolted to the bed by devices e e.

Device e consists in a bolt of the configuration shown, fitting over the top and side of the base of the rail, provided with a longitudinal slot in its threaded end, in which a wire 40 or metal blank is laid, and which, when the nut f is screwed up, is bent outward into one of a series of slots in the face of the nut, thereby locking the same. The bolts e pass through the blocks i and the bed O, and are screwed 45 down from underneath by the nuts f, whereby the rail D is securely held in place.

I claim—

1. In an elevated railway-bed, the stringer A, bed O, and fenders B C, formed from plate 50 metal, bent as shown, and bolted together to form the stringer A, constructed substantially as set forth.

2. The combination, with bed O B C, of bolt e and block i, as and for the purpose set forth. 55

JESSE LOCKHART.

Attest:

S. F. GREER,
JOHN SKELLY.
